TUNING SYSTEM

Bertram Trevor, Riverhead, N. Y., assignor to
Radio Corporation of America, a corporation
of Delaware

Application February 12, 1932, Serial No. 592,533

7 Claims. (Cl. 250—20)

This invention relates to radio signalling systems and more in particular to receiving systems having means for rendering the systems operative over a wide range of frequencies.

5 An object of systems of this type is to provide a receiver set which will be self contained and which will receive signals efficiently over a plurality of desired wavelength bands.

In general, the present receiver is of the type 10 which includes interchangeable inductances whereby a change of received frequency to several signalling channels of pre-determined width may be obtained merely by plugging in another set of tuning inductances.

15 Another object of this invention is to provide a radio receiver of the plug-in inductance type in which the inductances for interconnecting the several stages are included in separate shielded compartments, the several compartments comprising a separate container unit which may be 20 plugged in to the receiver as a unit to complete the circuits between the several stages in one operation, are not known in the art.

Broadly, the primary object of this invention 25 is to provide such a tuning arrangement.

In radio receivers adapted to cover a wide band of frequencies which comprise a plurality of stages and a plurality of interstage coupling inductances, each included in a separate shielded compartment, the several compartments composing a unit 30 which may be plugged into the receiver in one operation, extremely good shielding will result. Each inductance, however, will have considerable capacity coupling to its box or shielding compartment. This capacity becomes part of the coil's tuning capacity. At resonance the greatest current will flow through this capacity to the 35 grounded box. In this way the connection between the receiver ground and the metallic compartment enclosing the several interstage inductances is common to all of the tuned circuits. This gives rise to the transfer of energy between 40 said circuits. This in turn produces regeneration which results in an unstable amplifier.

45 An additional object of this invention is to provide a novel plug-in unit in which each of the interstage inductances is individually shielded and in which additional means is provided to prevent interchange of energy between the inductances of the several stages due to the fact that the composite shielding unit is in the path 50 to ground of all of the inductances.

In accordance with this invention the above 55 objects are accomplished by providing extremely efficient grounding between the inductance box

or container at points adjacent to the respective inductances. In a preferred embodiment of the present invention this grounding is accomplished by fixing to the receiver a plurality of spring contacts located at points such that the spring contacts make practically perfect contact with the metallic container for the inductances at points adjacent the several inductances. It will be understood that the contacts may be positioned at other convenient points without departing from 10 the spirit of the invention.

5 Another method of preventing interchange of energy between the inductances interconnecting the several stages is to provide separate shields for each coil and an insulating strip on which the 15 separate individual shields for the inductance are mounted. Each inductance container or coil box is then grounded to the receiver through a separate ground which may be a spring contact as described above. In this arrangement the 20 circuit from one coil box to ground is not common to the circuit from any other coil box to ground.

The novel features of my invention have been set forth in the claims appended hereto.

The nature of the invention and the operation 25 thereof will be understood by the following detailed description thereof and therefrom when read in connection with the drawing, throughout which like reference characters indicate like parts and in which:

30 Figure 1 shows diagrammatically an interstage coupling unit in which the several coupling means are individually shielded and in which the spring contacts for grounding the metallic coil box at points adjacent the several tuning means to the 35 receiver are shown;

35 Figure 2 is a plan view of a portion of a receiver showing the contacts of the present invention and sockets where the coil box is plugged in;

40 Figure 3 shows the coil box, the tuning means of the receiver proper, and the thermionic stages coupled by means of said inductances.

45 Referring to the drawing, and in particular to Figs. 1 and 3, C₁ C₂ C₃ and C₄ indicate ganged main tuning condensers with a single control K for tuning the receiver over the entire range. Each condenser has one armature connected to ground, which in this case is the metallic shielding MS for the receiver. The other armature of 50 each condenser is connected as shown to male contacts I, which as shown, extend through openings in the metallic shielding MS for the receiver so that when the inductance unit, to be described more in detail hereinafter, is plugged in, i. e. 55

placed in position on the receiver connection between the several inductances in said unit and the tuned capacities C_1 , C_2 etc. is complete.

A plurality of coupling inductances I are enclosed in a container T , each inductance being enclosed in an individual compartment formed by the shield partition members 3 . Each inductance has one terminal grounded as shown at 4 to the metallic member T at 4 , as shown and the other terminal connected to a female contact member 6 . The contact members 6 are positioned as shown adjacent insulated openings 8 in the shield T . When it is desired to change the range over which the receiver will tune, a unit T , having inductances of a predetermined inductive value, is plugged into the receiver, that is, is placed in such a position on the main condenser unit MS that the contacts 1 connected to the free ends of the condensers C_1 , C_2 etc., enter the openings 8 in the shield T of the inductance system, which openings are furnished with insulators 9 to make contact with the female contact members 6 connected with the free ends of inductances I , thereby completing the individual tuning circuits C_1 , I . In order that the capacity from the inductance to the box shielded circuit of each individual inductance I be separated, contacts in the form of springs S are fastened by rivets or screws 10 , as shown in Figure 2, to the top of the receiver shield MS . The springs S which may be composed of any metal and are preferably composed of bronze may be located in any position, preferably at points adjacent the point 4 (see Figs. 1 and 3) in each of the individual compartments of T when the unit is in position on MS or at other convenient points. When the unit T is placed in position on the receiver the contacts 1 enter the contacts 6 while the springs S bear tightly against the under surface of the unit T at spaced points therealong. Each of the inductances I and each tuning capacity C_1 are enclosed in separate compartments having no other openings except the opening 8 between the compartment in T , formed by the partitions 3 , and the opening in the receiver shield MS , formed by the partitions 5 . The relative position of the contact members 1 and 6 and springs S can be seen more clearly by reference to Figure 2 of the drawing.

The unit T is retained in position on the unit MS by spring clamps SC shown in Figure 2.

The tuning unit described above is applicable to any type of receiver known today, including receivers in which the several stages are coupled by transformer inductances. For purposes of illustration the unit has been shown to enclose inductances which may be used to interconnect thermionic relay stages, as shown in Figure 3. In Figure 3 the thermionic tubes 10 , 20 , 30 and 40 each have a grid electrode 11 , 21 , 31 and 41 connected as shown to the high potential terminal of capacities C_1 , C_2 , C_3 , C_4 , respectively and to the high potential terminal of an inductance I . The anodes 12 , 22 , 32 and 42 of tubes 10 , 20 , 30 and 40 respectively are supplied by direct current potential by inductances 13 , 23 and 33 respectively from a source $B+$. Alternating current potentials appearing on the anodes of the respective tubes are impressed on the grid of the following tube through coupling condensers 14 , 24 and 34 respectively. The cathodes 15 of each tube are connected as shown through biasing resistances R shunted by by-pass condensers BP to ground as illustrated. The potential variations appearing in the anode circuit of tube 40 may be applied to any load circuit as indicated. Screening elec-

trodes 16 are positively charged from a source S . G .

Balancing or trimming capacities C are connected in parallel with each of the main tuning condensers C_1 , C_2 etc., in order that they may be guarded to tune in step over their entire tuning range.

I claim:

1. Means for tuning a radio receiver over a wide frequency range comprising, a separate group of capacitive and inductive circuits, a plurality of individually shielded compartments having capacitive tuning means, a plug-in coil compartment including a plurality of individually shielded inductances, and means comprising separate contact members on each compartment for completing the circuits between each of the individually shielded compartment inductances and capacities when the plug-in unit is placed in position.

2. In radio receiver apparatus, a plurality of thermionic relays, means for coupling said relays in cascade including inductances, an individual shield for each inductance, said shields forming a unit, a tuning device comprising an individual shielded tuning unit for each of said inductances, contacts connected with each tuning unit, a contact connected with each inductance and extending through the shield for said inductance, said contacts adapted to connect said inductance with said tuning means when said inductance units are placed on said tuning means, and means for providing a short electrical path between the individual shields containing the tuning means and the individual shields containing inductances comprising a spring contact member mounted on the shield of the tuning unit and bearing directly on each individual inductance shield.

3. Means for tuning a radio receiver over a broad band of frequencies comprising a plurality of capacity units, each enclosed in an individually shielded compartment, said compartments comprising an enclosed single unit, a connection between one terminal of each of said capacity units and its shield, a contact member connected to the other terminal of said capacity, each contact member extending through an opening in its container and insulated therefrom, a plurality of inductances mounted in a shielded container, each inductance being individually shielded, there being a set of inductances for each frequency band, a connection between one terminal of each inductance and the shielded wall of its container, a contact member connected to the other end of each inductance and located adjacent an opening in said container, said contact members being spaced to plug into complementary contact members in said capacity units, and a spring contact member fastened to said first named enclosed single unit adjacent each inductance when the unit is plugged in.

4. Means for tuning a radio receiver over a wide frequency range comprising, a plurality of capacitive tuning means, individual shielding means and individual shield contacts for each tuning means, a plug-in coil compartment including a plurality of individually shielded inductances, and means comprising separate contact members on each compartment for completing a circuit between each inductance and one of said capacities when the plug-in unit is placed in position.

5. In radio receiver apparatus, a plurality of thermionic relays, means for coupling said relays in cascade including means for individually

shielding said coupling means comprising inductances, said individual shields forming a unit, a tuning device comprising a shielded variable capacity unit for each of said inductances, a contact connected with each capacity unit, a contact connected with each inductance and extending through the shield for said inductance, said contacts adapted to connect one of said inductances with each of said tuning capacities when 5
10 said inductance units are placed on said tuning means, and means for providing a short electrical path between the individual shields containing the tuning capacities and the individual shields containing said inductances comprising a spring 15
15 contact member bearing on each inductance shield when the unit is plugged in.

6. In radio receiver apparatus, a plurality of thermionic relays, means for coupling said relays in cascade including inductances, an individual shield for each inductance, said shields forming a unit, a tuning device comprising a shielded tuning unit for each of said inductances, contacts connected with each tuning unit, a contact connected with each inductance and extending 20
25 through the shield for said inductance, said contacts adapted to connect said inductance with

said tuning means when said inductance units are placed on said tuning means, and means for providing a short electrical path between the shields containing the tuning unit and the individual shields containing said inductances comprising a resilient metallic contact member bearing directly on each inductance shield. 5

7. In radio receiver apparatus, a plurality of thermionic relays, means for coupling said relays in cascade including inductances, an individual shield for each inductance, said shields forming a unit, a tuning device comprising a shielded tuning unit for each of said inductances, contacts connected with each tuning unit, a contact connected with each inductance and extending 10
15 through insulated openings in the shield for said inductance, said contacts adapted to connect said inductance with said tuning means when said inductance units are placed on said tuning means, and means for providing a short 20
25 electrical path between the shields containing the tuning device and each of the individual shields containing the said inductances comprising a spring contact member bearing directly on each inductance shield. 25
